UNITED STATES PATENT OFFICE.

JOHN THEOBALD, OF ARCHBOLD, OHIO, ASSIGNOR TO JOHN B. THEOBALD, JR.

HAND-PLANTER.

1,287,516.

Specification of Letters Patent. Patented Dec. 10, 1918.

Application filed September 10, 1917. Serial No. 190,611.

To all whom it may concern:

Be it known that I, JOHN THEOBALD, a citizen of the United States, residing at Archbold, in the county of Fulton and State of Ohio, have invented certain new and useful Improvements in Corn-Planters; and do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in a hand corn planter, and consists of a simple and efficient device of this nature having various details of construction, combinations and arrangements of parts which will be hereinafter fully described, shown in the accompanying drawings and then specifically defined in the appended claims.

My invention is illustrated in the accompanying drawings which, with the letters of reference marked thereon, form a part of this application, and in which:

Figure 1 is a front elevation of the device.

Fig. 2 is a central sectional view through the same showing the plunger raised, and

Fig. 3 is a central sectional view showing the plunger at its lowest limit.

Reference now being had to the details of the drawings by letters:

A designates a plunger having a handle B at one end and C is a hopper mounted upon a board D. A plate E has parallel flanges E' formed upon its longitudinal edges and which are fastened to the edges of said board, with a space intervening between the plate and the adjacent face of the latter, of sufficient size to receive said plunger. The portion of the plunger which has a reciprocating movement in said space is contracted as at A' and A² is a shoulder near the upper portion of said contracted part. The plate E has a struck up lug N shown clearly in Fig. 3 of the drawings and to which a block O is fastened, which latter forms a closure for the opening from which the lug is struck up, said lug serving as a foot-hold for use when it is desired to push the device into the ground. Said block serves as a means for limiting the distance that the lower end of the device is adapted to enter the ground.

Said plunger is provided with two longi-

tudinal slots designated by letters L and O, the former of which is adapted to receive the bolt L', which passes through the plate L², the ends of which are bent at angles and extend over the opposite edges of the plunger, tending to guide the latter in its reciprocating movement. Said bolt passes through the board D and serves to hold the latter and plunger together. An angled bar P, having an elongated slot therein, is mounted to have an adjustable movement within the slot O and the inner inclined portion P² of the plate P cooperates with the inclined end wall O' of the slot O to receive the kernels of corn or the seed to be planted. An adjusting screw M passes through the slot P' and engages a threaded hole in the plunger and through which means the angled plate may be held in different relative positions to feed different numbers of kernels. Said slot or recess formed in the end of the board, has an integral cross-piece F², the edge F³ of which is beveled, and which serves to retain kernels of corn for the last hill, after corn has been fed forward by the longitudinal movement of the plunger. It will be noted that the inner face of the plunger is provided with a recess A³ in which the corn falls as the plunger is driven back, so that the recess A³ will come underneath the cross piece F². The extreme end of the plunger is provided with a metal tip A⁴ which is adapted to drive the seed forward and pack the seed down after the nose of the device has been inserted in the ground.

A stripper T, preferably of pliable material, such as rubber, is fastened to the block T', held by means of a screw T² in a slot formed in the end of the hopper and which tends to smooth off the piles of kernels of corn which fall into the recess and before the plunger is fed forward. The upper end of said hopper is provided with a sliding door C' underneath which said board passes. The upper end D' of the board is contracted and is resilient and underneath the same is a transverse slot S through which one end of an angled plate passes and which latter is fastened to the under surface of the plunger. A link X has its two ends bent over the opposite edges of the contracted portion of the board and is provided with a loop portion X', which extends through said slot S and through which loop the angled end Y of the lever Y' passes and which lever is provided with pintles Y² pivotally mounted

in the ends of the plate Q, which is fastened to the under surface of the plunger.

The operation of my planter will be readily understood as follows:

- 5 Corn or other seed is placed in the hopper and when it is desired to feed the seed, the operator, by pushing the nose of the device in the ground may form a hole and by pushing the plunger down, seeds, which may fall 10 into the recess in the plunger, will be fed forward into the upper recess which is regulated by said angled plate T, and on the second operation of the plunger, the seed are permitted to fall by gravity into the 15 lower end of the plunger, thence down to the ground, and after passing the recessed end of the board, the plunger may be driven forward and force the seed underneath the surface of the ground.
- 20 When the ground is hard the operator, by pulling on the angled lever, may cause the board and plunger to frictionally engage each other, so that they may be moved together, for the purpose of forming a hole 25 in the ground, after which, by operating the plunger independently, it may be set forward in the usual way.

By the provision of a corn planter, made in accordance with my invention, the device 30 may be adjusted to fit different quantities of seed, the kernels of falling corn being held back by the recess in the board until the plunger makes a second operation.

What I claim to be new is:

- 35 1. A hand planter, comprising a recipro-

cating plunger with a recess in its inner face, said plunger having elongated slots therein, a board with a slot at one end and provided with an opening adjacent the upper end of the slot, an adjustable angle bar secured to 40 the plunger and passing through one of said slots therein, a plate having longitudinal flanges secured to the opposite edges of the board, a metallic tip on the plunger and movable between the flanges of the plate, and 45 a seed box upon said board.

2. A hand planter, comprising a reciprocating plunger with a recess in its inner face, said plunger having elongated slots therein, a board with a slot at one end and provided 50 with an opening adjacent the upper end of the slot, an adjustable angle bar secured to the plunger and passing through one of said slots therein, a plate having longitudinal flanges secured to the opposite edges of the 55 board, a metallic tip on the plunger and movable between the flanges of the plate, a seed box mounted upon said board, the upper end of the latter having a yielding struck-up portion, an angled lever pivoted to 60 the plunger, and a hook passing through the plunger and engaging over said contracted end and engaged by said angle lever.

In testimony whereof I hereunto affix my signature in presence of two witnesses.

JOHN THEOBALD.
